UNITED STATES PATENT OFFICE.

CHARLEY C. PURDY, OF GILEAD, MISSOURI.

DESIGN FOR A NUT-LOCK.

SPECIFICATION forming part of Design No. 27,427, dated July 27, 1897.

Application filed May 3, 1897. Serial No. 634,951. Term of patent 7 years.

To all whom it may concern:

Be it known that I, CHARLEY C. PURDY, a citizen of the United States, residing at Gillead, in the county of Lewis and State of Missouri, have invented and produced a certain new and original Design for Nut-Locks; and I do declare the following to be a full, clear, and exact description of the invention, such as will enable others skilled in the art to which it appertains to make and use the same.

My invention has relation to a new and original design for nut-locks; and it consists of a nut-lock of the configuration and ornamentation shown in the accompanying drawing, in which I have illustrated my invention in perspective.

The leading features of the invention consist in a plate approximately rectangular in form and having its corners beveled, as shown

at 2, and provided with elongated slots, as 20 shown at 3, the end walls of which are provided with laterally-projecting wings 4. Intermediate the ends of the plate is a series of rectangular openings 5, the end walls of which are provided with laterally-projecting 25 wings 6.

Having thus described my design, what I claim as new and original, and desire to secure by Letters Patent, is—

The design for a nut-lock, as herein shown 30 and described.

In testimony whereof I hereunto affix my signature in presence of two witnesses.

CHARLEY C. PURDY.
